ATTORNEYS.

UNITED STATES PATENT OFFICE.

WILLIAM C. UHL, OF GARY, INDIANA.

PHOTOGRAPHIC-FILM-DEVELOPING APPARATUS.

1,178,278.

Specification of Letters Patent.

Patented Apr. 4, 1916.

Application filed September 20, 1915. Serial No. 51,622.

To all whom it may concern:

Be it known that I, WILLIAM C. UHL, a citizen of the United States, residing at Gary, in the county of Lake and State of Indiana, have invented certain new and useful Improvements in Photographic-Film-Developing Apparatus, of which the following is a specification.

This invention relates to apparatus for developing photographic films, and its object is to provide a novel and improved means for carrying the film through the developing fluid whereby the developing process may be easily and quickly carried out, without employing a dark room.

The object stated is attained by means of a combination and arrangement of parts to be hereinafter described and claimed, reference being had to the accompanying drawing, in which—

Figure 1 is a plan view of the apparatus with the lid thereof removed; Fig. 2 is a longitudinal section of the apparatus, and Fig. 3 is a similar view showing an arrangement for developing films composed of separate sheets.

Referring specifically to the drawing, 5 denotes an ordinary wooden or other box provided with a removable lid 6. The box 30 contains a removable partition 7 dividing the same into two compartments 8 and 9, respectively. The partition is slidably mounted in grooves 10 in opposite walls of the box.

35 In the compartment 8 is located a pan or tank 11 containing the developing fluid 12, and in the compartment 9 is located a shelf 13, the same being mounted on the end wall of the box 5. This shelf has a slot 14 near its forward edge, the same being for a purpose to be presently described.

On that side of the partition 7 which faces the compartment 8 are mounted bracket arms 15 which support a reel shaft 16 on which the film roll 17 is wound. This shaft is located above the pan 11 adjacent to one end thereof, and adjacent to the same end of the pan, and also above the same is mounted a reel composed of shaft 18 and end disks 19. Adjacent to the opposite end of the pan, and above the same, is mounted a reel composed of a shaft 20 and end disks 21.

In the pan 11, adjacent to the ends thereof are guide rollers or spools 22 and 23, respectively, each comprising a shaft having

end disks. These guide rollers are journaled in the side walls of the pan and they extend across the pan at such a depth that they are immersed in the developing fluid 12.

60

The reel shafts 18 and 20 are journaled in the side walls of the box 5 and have crank handles 24 and 25 on the outside of the latter.

On the reel shafts 18 and 20 are fastened 65 the ends of a film carrier composed of a wide flexible band 26, having attached, to one side, adjacent to its edges, film spacing strips 27. The carrier is adapted to be wound on one reel as it is unwound from the 70 other. The spacing strips are flexible so that they wind and unwind with the band.

In operation, the carrier band 26 is made fast at one end and wound on the reel shaft 18, and its other end is made fast to the reel 75 shaft 20. The band passes down from the reel shaft 18 into the pan 11 and beneath the guide roller 22, and then extends forward through the pan to the guide roller 23, from which latter it passes upward out of the pan 80 to the reel shaft 20. That portion of the band which travels between the guide rollers 22 and 23 is therefore immersed in the developing fluid 12 in the pan. With the band in this position, the end of the film 17 wound 85 on the shaft 16, is made fast to the band between the reel shaft 18 and the guide roller 22, by means of paper clips or other suitable devices 28, the attachment being made to that side of the band which has the strips 90 27, the latter being for the purpose of spacing the sensitized face of the film from the band and also for holding the convolutions of film spaced apart on the reel 20. Upon 95 turning the reel 20, by means of the crank handle 25, in the direction of the arrow in Fig. 2, the band is wound off the reel 18 and onto the reel 20, carrying the film through the developing fluid 12 and winding it with the band on the reel 20. The crank handle 100 24 is provided for winding the band back on the reel 18.

For flat or separate films 29, the partition 7 is removed and the reel 18 is hung below and adjacent to the forward edge of the shelf 13 as shown in Fig. 3, the shelf supporting a box 30 containing the undeveloped films. The films are drawn out from the end of the box and after being passed through the slot 14 they are fastened, one 105 after the other, to the carrier band 26 as before. Above the guide roller 22 and above

110

the pan 11, is mounted a guide roller 31 to enable the band to clear the top of the pan. The band passes from the reel 18 to the guide roller 31, and then down to and under the 5 guide roller 22, from which latter it passes across the guide roller 23 and to the reel 20 as before. The crank handle 25 being turned as before, the band is wound off the reel 18 and on the reel 20, carrying the films 10 through the developing fluid 12 and winding the same on the reels 20 with the band.

By the apparatus herein described it is possible to develop films in the open sun-light, and a dark room is not necessary.

15 I claim:—

1. A photographic developing apparatus, comprising an inclosure, a pan in the inclosure containing the developing fluid, guide rollers in the pan adjacent to the ends thereof and immersed in the developing fluid, 20 reels mounted above the pan adjacent to the ends thereof, a flexible film-carrying band secured to its ends to the reels and adapted to be wound off one reel onto the other, that portion of the band which is between the reels passing into the pan and under the 25 guide rollers therein, and a film-supporting member mounted adjacent to one of the reels.

30 2. A photographic developing apparatus, comprising an inclosure, a pan in the in-

closure containing the developing fluid, guide rollers in the pan adjacent to the ends thereof and immersed in the developing fluid, 35 reels mounted above the pan adjacent to the ends thereof, a flexible film-carrying band secured at its ends to the reels and adapted to be wound off one reel onto the other, that portion of the band which is between the reels passing into the pan and under the 40 guide rollers therein, a film-supporting member mounted adjacent to one of the reels, and means on the band for spacing the face of the film therefrom.

3. A photographic developing apparatus, 45 comprising an inclosure, a pan in the inclosure containing the developing fluid, guide rollers in the pan adjacent to the ends thereof and immersed in the developing fluid, 50 reels mounted above the pan adjacent to the ends thereof, a flexible film-carrying band secured at its ends to the reels and adapted to be wound off one reel onto the other, that portion of the band which is between the reels passing into the pan and under the 55 guide rollers therein, a film-supporting member mounted adjacent to one of the reels, and film-spacing strips on one side of the band adjacent to the edges thereof.

In testimony whereof I affix my signature 60 in presence of two witnesses.

WILLIAM C. UHL.

Copies of this patent may be obtained for five cents each, by addressing the "Commissioner of Patents, Washington, D. C."
